UNITED STATES PATENT OFFICE.

ALOIS HÜLA, OF PILSEN, AUSTRIA-HUNGARY.

ROTARY MOTOR.

SPECIFICATION forming part of Letters Patent No. 783,865, dated February 28, 1905.

Application filed November 11, 1903. Serial No. 180,742.

To all whom it may concern:

Be it known that I, ALOIS HÜLA, a subject of the Emperor of Austria-Hungary, and a resident of Pilsen, Bohemia, Austria-Hungary, have invented certain new and useful Improvements in Rotary Motors; and I do hereby declare the following to be a full, clear, and exact description of the invention, such as will enable others skilled in the art to which it applies to make and use the same.

My invention relates to a rotary steam or like motor.

In the accompanying drawings, Figure 1 is a vertical section of the motor, taken on the lines I I and II II of Fig. 2. Fig. 2 is a horizontal section taken on the lines III III and IV IV of Fig. 3. Fig. 3 is a vertical cross-section on the lines V V and VI VI of Fig. 2. Figs. 4 to 15 show details to be hereinafter referred to.

The motor consists of the steam-cylinder *a*, provided with covers *b b'* and steam-regulating chambers *c c'*, of the shaft 7, slide *e*, valve *g*, and governor *i*. From either side of the motor two passages 1 1' and 2 2' conduct from the steam-chambers *c c'* into the steam-cylinder *a*, Figs. 1 to 3, 6, 7, for the live-steam supply and for exhaust, respectively. Each of the upper passages 1 1' branches into two channels leading from the body of the cylinder to the covers *b b'* and entering the chamber of the cylinder at 3 and 3' adjacent to the slide *e*. These passages remain open for permanent supply of steam, the latter being regulated by slide-valves 4 and 4' in the steam-chambers *c c'*. The lower passages 2 2' likewise bifurcate into two channels, which enter the cylinder-chamber at 5 and 5' and are closed by valves 6 and 6' in the steam-chambers.

In the steam-cylinder *a* is a working member *d*, Figs. 1 to 3, 8 to 12, keyed to the shaft 7 and comprising a cylinder 8 and a flange or ring consisting of two separate sectors 9 and 9', of which the one is located at one end of the cylinder and the other one at the opposite end in such manner that they stand at an angle of one hundred and eighty degrees relative to each other. These two sectors 9 9' are connected with each other by screw-blades

10 and 10', of which the one, 10, is right-handed and the other, 10', left-handed.

Figs. 8 to 10 show side elevations of the member *d* with its flange in three different positions. Fig. 11 shows an end elevation of the same, and Fig. 12 a section on the line VIII VIII of Fig. 8.

The slide *e*, Figs 1, 2, 13 to 15, has the form of a long plate and is with one of its narrow sides, 11, always bearing against the surface of the cylinder 8, Figs 1, 8 to 10. It is provided at the center with a recess 12, in which the flange of the cylinder 8 engages, so that the slide is moved positively to and fro. At either side of the recess 12 are jaws 13 13', pressed against the flange of the cylinder 8 by springs 14 for the purpose of making tight joints. The slide *e* is pressed against the cylinder 8 by the plate 15, which again is under the influence of the spring 16. The jaws are chamfered at their inner edges, so that the surfaces 17 lie against the sectors and the inclined faces 17' against the screw-blades.

The valve *g*, Figs. 1 to 5, consists of a casing 18, to which four pipes are bolted—viz., the pipe 19 with valve 20 for the steam-supply, the pipes 21 and 21' connecting the valve *g* with the steam-chambers *c c'*, and finally the exhaust-pipe 22. Inside the casing 18 is a conical valve-body 23, having two chambers and mounted on a spindle. The valve-body 23 can be adjusted in three different positions *m*, *n*, and *o* for the various steamways. In the position *m* the steam-supply is cut off. In position *n* steam enters the pipe 21, and in position *o* steam enters the pipe 21'. 85

The speed of the motor is controlled by the governor *i*, driven from the shaft 7 by means of pulleys 24 and cord 25.

26 is a sliding sleeve to which is connected the double arm 27, which by means of rods 90 work the slide-valves 4 4', which close and open the passages 1 1'.

After opening of the valve *g* into the position *n* steam enters the pipe 21 and chamber *c*, and from here through the passage 1 and the two holes 3 at the side of the slide *e* into the steam-cylinder. The steam cannot escape through the passage 2, as the valve 6 is forced

down by the live steam above. The steam reaches the cylinder 8 and enters the chambers s and s' , Fig. 8, which are enlarged by the steam-pressure, and thus set the cylinder 5 8 in rotation. The steam-supply passages are closed at the proper moment and the chambers filled with steam arrive at the other side of the slide, where the steam commences to rush out through the holes 5' and passage 2' 10 into the steam-chamber c' . When this passage 2' no longer suffices, the exhaust-steam also flows through the passage 1'. From the steam-chamber c' the exhaust-steam flows through the pipe 21' into the valve g and into the exhaust-pipe 22 in the direction of the arrows t . According to Fig. 8, where the slide divides the two steam-chambers r and s into two parts, the steam enters from the side s and s' and escapes at r and r' and the cylinder rotates in 15 the direction of the arrow v . According to Fig. 9 the sector 9 enters between the surfaces 17 of the jaws 13 and 13' and remains in this position also in Fig. 10, where the steam only exerts pressure in the chamber s' , since the 20 passage 3 is closed against the chamber s by the sector 9. On further rotation of the screw-blade 10' a new chamber s is formed and the steam-pressure commences to act again in it, so that there can never be a dead-point, and 25 30 35 40 45 50 55 60 65 70 75
